PUMP AND MOTOR

Elek K. Benedek, Chicago, Ill.

Application November 3, 1944, Serial No. 561,736

8 Claims. (Cl. 103—161)

1

This invention relates to variable delivery pumps and motors, such as described and claimed in my co-pending application, Serial No. 694,179, dated November 18, 1933, now Patent 2,255,962 granted September 16, 1941. One object of the present invention is to provide improved reactance means for greater operating speed and pressure.

Further object is to provide improved and self-contained piston and cross pin assemblies with permanent and life-long lubrication therein, between the rolling cross pins and the cross pin bore of the radial heads of the pistons.

Still further objects are the provision of self-contained piston and roller assemblies with permanent life long lubrication between thrust rollers and stationary thrust pins of the radial piston heads.

Still further objects will be apparent and more particularly described in connection with the accompanying drawings forming part of this specification.

In the drawings:

Fig. 1 is a partial longitudinal main section, taken on line 1—1, in Fig. 2, of the pump, constructed in accordance to the spirit of this invention.

Fig. 2 is a transverse main section, taken on line 2—2 of Fig. 1, some of the pistons being shown in elevation, some of them in partially sectional elevations, for the clearance of the illustration.

Fig. 3 is a longitudinal main section of a pump, constructed in accordance with the spirit of this invention, showing a modification thereof.

Fig. 4 is a partial longitudinal sectional view of a self-contained piston and anti-frictionally mounted rolling cross pin assembly, showing parts of the piston and cross pin in elevation, taken thru line 4—4 in Fig. 5.

Fig. 5 is a partial sectional view, taken on line 5—5 of Fig. 4, showing the piston and cross pin sub-assembly.

Fig. 6 shows the spring snap-ring, used in connection with the sub-assemblies of Fig. 4 and Fig. 5, for retaining the rolling cross pins of the piston sub-assemblies in place.

Fig. 7 is a partial, longitudinal sectional view of my novel self-contained piston roller sub-assembly and is slightly modified relative to the one shown in Fig. 1 and Fig. 2, taken on line 7—7 in Fig. 8.

Fig. 8 is a sectional view taken on line 8—8 of Fig. 7.

Fig. 9 is a spring snap ring, used to retain the

2

rollers on the protruding ends of the rigid cross-pins in Fig. 7.

Figure 10 is a transverse vertical section on the line 10—10 of Figure 3.

Figure 11 is a fragmentary section on the line 11—11 of Figure 1.

Figure 12 is a fragmentary section on the line 12—12 of Figure 3.

Referring to Figs. 1 and 2 of the drawings, they show the inside of a reversible variable delivery pump in which the cylinder block 2 and a rotary reactance 14—15 are associated by the medium of the pistons 8—9 and cylinder assemblies 7, including the cross-pins 10 of the pistons, and the coaxing thrust rollers 11.

Each piston 8 has a large radial head as at 9, having cylindrical or flat torque transmitting and guiding surfaces as at 9a, which cooperate with complementary radial guiding and torque transmitting surfaces 20a of the central circular flange 20 of the barrel 2. It will be noted, that in case of a hydraulic motor, the entire torque and therefore the entire utility of the motor will be concentrated on these surfaces and consequently they must be large enough to sustain an effective oil film, during maximum pressure operation periods. For this reason the radial heads 9 are not only long, at least as long as the length of the pistons 8, but they are also larger than the diameter of their piston.

In the embodiment of Fig. 1, Fig. 2, Fig. 7 to Fig. 9 and Fig. 11 inclusive, the reactance halves 14 and 15 are bolted together as at 16, to form a fluid tight reservoir for the slip fluid of the pump, and collect this slip fluid, for the purpose of full and effective lubrication of the guide 20a and piston head 9.

It will be seen that by the virtue of this rotary liquid tight reactance drum 14—15 the thrust elements of the piston head 9, such as the rigidly secured cross-pin 10, 10a, 10b and 10c, and the associated roller bearing assembly 13 and the roller sleeve 11, all will operate during all sustained pressure cycles in a bath of oil. At higher speeds such as 1000 to 2500 R. P. M., this lubricating rotary oil bath will be subject to substantial centrifugal pressure, and it will additionally help the lubrication and cooling of the elongated roller elements 13.

Cross-pin 10 has an enlarged center portion as at 10a as more specifically shown in Fig. 11, rigidly secured in a complementary transverse bore of the head 9 by heavy press or shrinkfit. Each protruding end 10a—10a of the pin is provided with a retaining flange 10b and a groove to re-

ceive a spring snap ring 12, to retain elongated roller bearings 13, which support the pin-ends 10a-10a by means of roller sleeves 11-11 on coacting circular thrust shoulders, of the reactance halves 14 and 15. In this embodiment the pin ends are of the same diameter as the thrust ends of the pin 10, and the snap retainer ring 12 retains the rollers 13 in assembly, when the piston is removed from its cylinder. The diameter of the snap ring 12 is greater however than the bore of the roller sleeve 11, so that the snap ring retains not only the roller bearings, but also the roller sleeve 11 on the thrust pin 10.

The large piston head 9 readily accommodates the enlarged central portion of the pin 10, to minimize elastic deflection of the pin ends 10a-10a. This is very essential, since the roller bearings 13 and the sleeve 11 take up substantial space radially of the pin and the pin ends themselves must be substantially weaker than the middle portion.

The radical piston load of the rotary pistons will be transmitted during each revolution to the reactance shoulders of 14 and 15 in form of a sharp shock-load, since the time element of one pressure stroke is very small. Assuming conventional pump speeds of 1200-1800 R. P. M.'s, the entire compression stroke will take $\frac{1}{20}-\frac{1}{30}$ of a second. The shock itself has much shorter duration however, even at the special V-notch pintle port construction, which is directed to absorb shock by the V-notch port openings. Considering the duration of the shock itself, it is a mere fraction only of the entire pressure stroke.

To absorb the above destructive shock, and yet to apply anti-friction elongated roller bearings for load and primary torque transmission, I submerge the entire roller bearings 13 in the above specifically described oil bath, so that at least at higher pressure when the pressure slip maintains the bath, continuously during pressure cycles, the rollers will be submerged in oil. At lower pressures the centrifugal force retains the oil bath in the drum, and therefore it may be said that the thrust roller bearings of the pistons are submerged in an oilbath during substantial periods of all working cycles.

The tenacious oilfilm surrounding the closely disposed but freely rotating needle rollers in such a manner that each bearing will have a high load carrying capacity combined with shock absorbing quality. In addition, the rolling frictional engagement between cylinder block 2 and reactance ring 14-15, in case of hydraulic motors will behave consistently with respect to starting torque under variable temperature conditions of the oil, when the variation of viscosity causes serious variations in starting torques of conventional motors, applying sliding oil film bearings as thrust means at the outer ends of the pistons.

Since in case of deflection of the cross pins 10 under heavy loads, the cageless elongated rollers trend to skew considerably and move axially against the snap rings 12-12, in Figs. 7 and 8 I make a primary shoulder as at 10b to withhold the needles and a secondary shoulder as at 10a to withhold the snap ring 12. Under all conditions, the elastic deflections of the pin ends 10c-10c must be prevented, to eliminate destructive skewing of the rollers. I accomplished the above objectives by providing heavier portions in the middle than at the ends of the pins, and additionally by pressfitting the pins 10

in the piston heads 9 so that deflections really start, where the enlarged middle portion ends and the pin ends begin. This connection of the small ends with the enlarged center portions must be additionally relieved from shearing stresses by a radius as shown at 10d, which radius further facilitates the elimination of the skewing of the roller bearings, by keeping the pin ends straight and permitting the concentration of bending forces to the radius itself. The ends 12a of the snap rings 12 do not touch each other so that it may be freely expanded or contracted for its insertion into the complementary groove of the pin ends.

15 The elongated rollers are disposed with a capillary circumferential clearance with respect to each other in the bearing assembly, so that once the bearing is lubricated, capillarity will hold the lubricant in the bearing, for long periods of times, some times for the entire life of the machine. This is important after transportation or shut down of the pumps, when ordinarily the lubrication is stopped or destroyed, so that during the next full load operation 25 the bearings would wear or burn out rapidly, before the necessary lubrication is supplied.

The embodiments of Fig. 3 to Fig. 6, Fig. 10 and Fig. 12 show a modification of the invention, wherein for radial space limitation neither 30 the roller sleeves 11-11 nor the liquid tight drum construction as at 14-15 can be used. In this instant, the rollers 13 are disposed in the piston head 9 itself and the snap rings are disposed in such a manner that one ring 12 prevents the movement of the pin in one direction while the other ring 12 prevents the movement of the pin in the opposite direction, by being pushed against one or the other recess 9c-9c, employed in the lateral faces of the head 9. 35 The outside diameter of the recess 9c is greater than the diameter of the bore of the crosshead, so that the snap rings 12 may be inserted into the grooves of the pin 10, by spreading the ring slightly under its elastic tension. For this purpose the inner inside edges of the snap rings are chamfered at about 30° to start them up easily on the pin ends 10c. The arrangement is such that the outer faces of the rings and the transverse faces of the piston crossheads will be flush with each other and lie in the same plane. This will facilitate the guiding of the piston and its head between the opposed plain faces of the reactance rings 33 and 34 of Fig. 3, thereby effecting a relative rotation for the pin 10 parallel not only with the axis of pintle 1, but also about its own axis and in such a manner, that this axis will remain parallel with itself and with the main axis of rotation of the pump in all adjusted stroke position of the pump.

60 It is important that by this guided arrangement of the piston head, during the absolute and relative rotation of each crosshead pin, skewing of the pin itself as well as skewing of the individual elongated rollers will be limited to a practical minimum.

65 In this solution it is further of utmost importance to keep the pins 10 parallel with the axis of the pintle and evenly distribute the load on each end of each pin, because in case of transverse misalignment of the pins, one or the other ends of the needle rollers will be pinched between the pin and the bearing bore, with consequent result of vehement skewing of the needles.

70 In my U. S. Patents 2,101,829 and 2,111,657 the

roller bearings are disposed in the same manner as in Fig. 3 to Fig. 5 of this application, with the exception that in the said patents the roller bearings are retained by end rollers rigidly secured to the pin ends.

In my co-pending application Ser. No. 716,451, filed March 20, 1934, now Patent 2,166,717 granted July 8, 1939 the roller bearings are disposed also in a similar manner, with the exception, that the pins and the pistons do not form a self contained sub-assembly, therefore in case of a disassembly or assembly of the pump, the needles may fall out with the pins from the crossheads, and get lost or it takes additional time for their reassembly. It will be noted, that the solution of Figs. 4, 5 and Fig. 12 affords a stronger pin, but it is necessary in this case, since the elastic deflection of each pin now will be proportional to the entire working length of the pin, while in case of Figs. 7, 8, and 11 the deformation extends only to the short stub ends of the walled-in pins.

In case of the latter solution, as shown in Figs. 4, 5 and 12, the deflection is the greatest in the middle, just where the roller bearings are, but here the rigid head bore comes to reduce the deflection. At the same time the curvature of the pin ends at 10c—10c will not matter much. In both instances I obtained a compactness in combination with a self contained piston-thrust mechanism, for high speed, high pressure and consistent torque performance of the motor which was unknown heretofore. Additionally, the arrangement is such, that capillary oilfilm lubrication and accompanying shock-absorbing qualities of the thrust roller bearings are assured at all speed and operating pressures.

These shock-absorbing qualities will be appreciated in view of the well known facts, that ordinary widely spaced roller bearings dig into the race tracks at short strokes and high pressures.

In variable pitch propellers, the thrust bearings dig in deeply into the race, while the propeller pitch remains constant, unless there are used 5 to 6 sets of thrust bearings. This galling phenomenon of molecular affinity, which exists between point contacts of widely spaced rollers and steel races, prevented heretofore successful application of anti-friction elements at the thrust transmitting ends of the pistons in high pressure pumps and motors, and limited the safe maximum pressure in variable displacement pumps and motors. It must be borne in mind that the utility of motors is particularly bound to good starting torque and efficient running torque characteristics which from the other hand is identical with successful application of anti-friction thrust transmission at the pins 10, or pin ends 10c.

Figs. 3 and 10 show particularly such an efficient thrust transmitting arrangement for hydraulic pumps and motors. It is now well illustrated in Fig. 10 that rotary crosspins 10 and rotary reactance groove-ways formed between inner and outer reactance halves 22—22 and 33—34 form an efficient rolling device which is capable for high speed and heavy rolling load transmission. Such a rolling device is not only capable of performing according to up-to-date standards, but due to the reduced masses of the straight cylindrical rolling pins 10 they introduce new avenues in pump design with their reduced size, weight and reciprocating inertia. These new features and their usefulness is further enhanced by the ability of the light retainer means, such

as 12—12 as in Fig. 12, to keep the pins centered with respect to their associated crossheads, and thus maintain an end space at both ends of said pins between the pin ends and the respective 5 radial walls of reactance halves 33 and 34. It will be seen that the possibility of the maintenance of this free space at the pin-ends, and the elimination of the scraping action between the side walls of the reactance and the pin-ends 10 is greatly dependent on the effective cooperation of retainer means 12—12. Also the effective end retention of needle rollers and the reduction of their tendency to skew is greatly accomplished by the same retainer rings 12—12.

Fig. 10 shows the piston and reactance assemblies in neutral position, therefore the circumferential spacing of pin-ends 10c—10c in the groove-ways is uniform. During operation this spacing however changes, and it will be appreciated that the tendency of the pin-ends 10c—10c to skew will be greatly minimized if the pins will be centralized with respect to the center lines of the pistons; the end scraping of the side walls of the reactance 33—34 will be eliminated by 20 the guiding and retaining means 12—12. In accordance with the spirit of the invention, in high speed machinery a straight crosspin 10 is used having intermediate bearing portion as at 10 in Fig. 12, and the end portions 10c—10c, 25 hardened and ground to assume the role of anti-friction bearing rollers, while the side portion 10 will assume the role of an inner race or shaft of an anti-friction roller bearing. The smaller the diameter of the crosspin 10 and the associated bearing structure, such as 10—13 and 9b, the better will this thrust transmitting structure approach the ideal conditions, the conditions of a precision, anti-friction, high speed roller bearing.

In the above described invention this galling 30 is eliminated by bath and capillary lubrication, combined with centrifugal pressure lubrication. Additionally the elongated roller bearings, although they do operate as roller bearings in metal to metal rolling contact with the thrust rollers, 35 are enveloped at all times with full oil film, and even without the bath, are able to operate efficiently under heavy loads. Good lubrication eliminates redrawing of the hardness of the needles, pins and races, and reduces wear to a commercial minimum.

To this effect, reactance halves 33 and 34 are 40 covered with sheet metal shell as at 35 to retain slip fluid in all inter spaces of the reactance assembly including the cylinder barrel and piston assemblies. Even when rotation stops, the lower 45 half of the fluid tight reactance retains sufficient fluid to supply good lubrication again, upon the restarting of the pump, when the retained fluid will be spread out over all of the enclosed parts within the halves 23—24 and the oil retainer shell 35 respectively.

The pump is enclosed in a cylindrical housing, 50 comprising a body portion 29 and two end plates as at 30 and 31 in a conventional manner. A reactance ring 19, stationarily mounts bearing supports 27—27 and associated ball bearings 17—65 17 in a well known manner. Finally these bearings will rotatably support the reactance halves 33—34 and the entire reactance thrust assembly 70 in the stationary reactance 19 during all adjusted position of the stationary reactance ring in the housing. It remains an outstanding feature of my invention, that the stationary reactance 19 is supported throughout its entire length 75 in the main body 29 of the pump, to thereby

distribute the reactance load on a large area and in the zone of the working reaction of the pistons.

Pintle 1, barrel 2 and impeller shaft 3 are arranged in a conventional manner. A key element 4 engages the shaft 3 and the barrel 2 for joint rotation.

Snap rings 26 and 28 retain the bearings 17 and the bearing rings 27 in their proper assembly against transverse forces such as the axially floating adjustment of the barrel and reactance assembly, by means of the impeller shaft. Cap screws 32 secure the end plates to the body so that the pintle 1 may be secured and supported at one end in one of the end plates while the drive shaft 3 and the adjoining end of the pintle be indirectly supported in the other of the end plates.

Various changes may be made in the embodiment of this invention, without departing from or sacrificing the advantages as hereinabove specifically described and claimed in the appended claims.

I claim:

1. In a rotary radial piston pump or motor, a rotor; radial cylinders and cooperating pistons carried thereby; operating head portions on the pistons respectively and having radially disposed side faces; each of said head portions having a bore extending parallel to the axis of the rotor; a plurality of thrust pins one received in each bore and protruding therefrom at each end; elongated roller bearings intervening between each thrust pin and the associated bore wall; reactance means surrounding said cylinders and including inner and outer trackways on opposite sides of the piston head portions, said reactance means comprising axially separable side members respectively providing said radially extending portions and said outer trackways, a pair of intervening ring members between said side members on opposite sides of the pistons and cylinders and providing the inner trackways, and means for securing said inner and outer trackways in assembled relation; the protruding ends of the thrust pins being adapted for rolling engagement with the inner and outer trackways, and lying respectively between the side faces of the reactance side members, means to maintain operative relation between said roller bearings and said pins in the bores of said head portions respectively, each piston and associated pin and roller bearing assembly forming a unitary piston-roller structure, said means comprising snap rings lying in face to face relation to the ends of the associated bores and being of greater diameter than said bores for retaining the elongated roller bearings and the thrust pins in operative position with the pistons and piston heads respectively, said pin ends being grooved to receive said snap rings and hold them against axial movement.

2. In a rotary radial piston pump or motor, a rotor; radial cylinders and cooperating pistons carried thereby; operating head portions on the pistons respectively and having radially disposed side faces; each of said head portions having a bore extending parallel to the axis of the rotor; a plurality of thrust pins one received in each bore and protruding therefrom at each end; elongated roller bearings intervening between each thrust pin and the associated bore wall; reactance means surrounding said cyl-

inders and including inner and outer trackways on opposite sides of the piston head portions, said reactance means comprising axially separable side members respectively providing said radially extending portions and said outer trackways, a pair of intervening ring members between said side members on opposite sides of the pistons and cylinders and providing the inner trackways, and means for securing said inner and outer trackways in assembled relation; the protruding ends of the thrust pins being adapted for rolling engagement with the inner and outer trackways, and lying respectively between the side faces of the reactance side members, means to maintain operative relation between said roller bearings and said pins in the bores of said head portions respectively, each piston and associated pin and roller bearing assembly forming a unitary piston-roller structure, said means including a pair of removable snap rings, a recess in each protruding end of the thrust pins to engage said snap rings, the outer diameter of said ring being larger than the bore of the head portions to engage the lateral faces of said head portion, and thereby retain said pin and said head portion in a unitary piston roller structure, said pins having substantially the same diameter throughout their entire length.

3. In a rotary radial piston pump or motor, a rotor; radial cylinders and cooperating pistons carried thereby; operating head portions on the pistons respectively and having radially disposed side faces; each of said head portions having a bore extending parallel to the axis of the rotor; a plurality of thrust pins one received in each bore and protruding therefrom at each end; elongated roller bearings intervening between each thrust pin and the associated bore wall; reactance means surrounding said cylinders and including inner and outer trackways on opposite sides of the piston head portions, said reactance means comprising axially separable side members respectively providing said radially extending portions and said outer trackways, a pair of intervening ring members between said side members on opposite sides of the pistons and cylinders and providing the inner trackways, and means for securing said inner and outer trackways in assembled relation; the protruding ends of the thrust pins being adapted for rolling engagement with the inner and outer trackways, and lying respectively between the side faces of the reactance side members, means to maintain operative relation between said roller bearings and said pins in the bores of said head portions respectively, each piston and associated pin and roller bearing assembly forming a unitary piston-roller structure, said means lying in face to face relation to the ends of the associated bores and being of greater diameter than said bores for retaining the elongated roller bearings and the thrust pins in operative position with the pistons and piston heads respectively, and including a pair of circular recesses in the end portions of the pin, a snap ring having radially disposed walls and adaptable in said recess, a complementary recess in the radial faces of the head portion adjoining the bore, the lateral depth of said recess being equal to the thickness of said ring, said circular recess of the pin engaging the inner portion, said outer recess of the head the outer portion of the radial walls of said snap ring, the diameter of said outer recess being greater than 75 the diameter of the ring to accommodate the

insertion of said ring into the inner recess of the pin during assembly.

4. In a rotary radial piston pump or motor, a rotor; radial cylinders and cooperating pistons carried thereby; operating head portions on the pistons respectively and having radially disposed side faces; each of said head portions having a bore extending parallel to the axis of the rotor; a plurality of thrust pins one received in each bore and protruding therefrom at each end; elongated roller bearings intervening between each thrust pin and the associated bore wall; means to maintain operative relation between said roller bearings and said pins in the bores of said head portions respectively, each piston and associated pin and roller bearing assembly forming a unitary piston-roller structure, said means comprising snap rings lying in face to face relation to the ends of the associated bores and being of greater diameter than said bores for retaining the elongated roller bearings and the thrust pins in operative position with the pistons and piston heads respectively, said pin ends being grooved to receive said snap rings and hold them against axial movement.

5. In a rotary radial piston pump or motor, a rotor; radial cylinders and cooperating pistons carried thereby; operating head portions on the pistons respectively and having radially disposed side faces; each of said head portions having a bore extending parallel to the axis of the rotor; a plurality of thrust pins one press-fitted in each bore and protruding therefrom at each end; elongated roller bearings intervening between each thrust pin and the associated bore wall; means to maintain operative relation between said roller bearings and said pins in the bores of said head portions respectively, each piston and associated pin and roller bearing assembly forming a unitary piston-roller structure, said means comprising snap rings lying in face to face relation to the ends of the associated bores and being of greater diameter than said bores for retaining the elongated roller bearings and the thrust pins in operative position with the pistons and piston heads respectively, said pin ends being grooved to receive said snap rings and hold them against axial movement.

6. In a rotary radial piston pump or motor, a barrel having radial cylinders therein, valve means for the cylinders, pistons in the cylinders respectively, heads on the pistons respectively, a transverse bore in each head, a rotary reactance surrounding the barrel in eccentric relation thereto and having radial side walls and normally aligned circular trackways respectively lying alongside the heads of the pistons, load transmitting rollers rotatably mounted at their center portion in the bores of the heads and having end portions in load transmitting rolling engagement with the trackways of said reactance, and retainer means carried by said center portions of the rollers and engaged by the end of said bores to retain said center portion in operative position in said bore.

7. In a rotary radial piston pump or motor,

a barrel having radial cylinders therein, valve means for the cylinders, pistons in the cylinders respectively, heads on the pistons respectively, a transverse bore in each head, a rotary reactance surrounding the barrel in eccentric relation thereto and having radial side walls and normally aligned circular trackways respectively lying alongside the heads of the pistons, load transmitting rollers rotatably mounted at their center portion in the bores of the heads and having end portions in load transmitting rolling engagement with the trackways of said reactance, and retainer means carried by said center portions of the rollers and engaged by the end of said bores to retain said center portion in operative position in said bore, said retainer means being arranged in paired assemblies at opposite ends of the center portions of said rollers.

8. In a rotary radial piston pump or motor, a barrel having radial cylinders therein, valve means for the cylinders, pistons in the cylinders respectively, heads on the pistons respectively, a transverse bore in each head, a rotary reactance surrounding the barrel in eccentric relation thereto and having radial side walls and normally aligned circular trackways respectively lying alongside the heads of the pistons, load transmitting rollers rotatably mounted at their center portion in the bores of the heads and having end portions in load transmitting rolling engagement with the trackways of said reactance, and retainer means carried by said center portions of the rollers and engaged by the end of said bores to retain said center portion in operative position in said bore, said retainer means being arranged in paired assemblies at opposite ends of the center portions of said rollers, each of said retainer means including a roller-groove and a retainer ring, the outside diameter of said ring being greater than the diameter of said bore, the inside diameter of said ring being smaller than the diameter of said roller.
